UNITED STATES PATENT OFFICE.

JOSEPH HOLDING, OF MANCHESTER, COUNTY OF LANCASTER, ENGLAND.

WHIP.

SPECIFICATION forming part of Letters Patent No. 312,719, dated February 24, 1885.

Application filed July 11, 1884 (No model.)

To all whom it may concern:

Be it known that I, JOSEPH HOLDING, a subject of the Queen of Great Britain and Ireland, residing at Manchester, in the county of 5 Lancaster, England, have invented a new and useful Improvement in Whips, of which the following is a specification.

This invention consists in an improved butt-joint between the lash or thong of a whip and its handle, whereby I insure a proper position of the lash at all times for immediate use by permitting it to turn automatically independent of the handle, and also obviate the tendency of the lash to break near where it is 15 attached to the handle.

It also consists in a peculiar construction of one of the parts, whereby a rivet-pin having projecting heads at both ends is accommodated, as means for securing the inner ferrule 20 on the large end of the lash or thong, and friction in the joint is reduced, as hereinafter set forth and claimed.

A sheet of drawings accompanies this specification as part thereof.

Figure 1 of the drawings is a side view of 25 a mid-length portion of a whip, partly in section, illustrating a preferred construction of the whip according to this invention. Fig. 1^x represents a cross-section on the line *xx*, Fig. 30 1. Fig. 2 is a sectional side view of a mid-length portion of another whip, illustrating a modification of the same invention; and Fig. 2^y represents a cross-section on the line *yy*, Fig. 2.

Like letters of reference indicate corresponding parts in the several figures.

In carrying out my invention I employ a handle, *H* or *H*², and a lash, *L* or *L*², each of 40 any approved material and style, and I unite the same end to end by a swiveling butt-joint, *S* or *S*². Said swiveling butt-joint is in each case formed by a pair of metallic ferrules, *a* *b*, of which said ferrule *a* is tightly fitted to the large end of the lash, and preferably 45 secured thereon by a transverse rivet-pin, *c*, while said ferrule *b* embraces said ferrule *a* and is fitted at its inner end to the small end of the handle, upon which it may be accommodated by a shoulder, *d*, and fastened by a 50 pin, *c*, or in any approved way, being in each case adapted to protrude beyond the handle end one-half its length, more or less, and

terminating in a contracted outer end, *b'* or *b*², fitted to the corresponding end or neck, *a'* or *a*², of the inner ferrule, *a*. Beyond its neck *a'* 55 in said joint *S*, Figs. 1 1^x, the inner ferrule, *a*, has a pair of circumferential beads, to coact with the inner walls of the outer ferrule, *b*, and its contracted outer end, and an annular space, *f*, between said beads accommodates 60 rounded heads on the rivet-pin *c*. In said joint *S*², Figs. 2, 2^y, said neck *a'* of the inner ferrule is formed by contracting this portion of the ferrule upon the lash, and this ferrule may be so held fast on some makes of lash, 65 while the rivet-pin *c*, if employed within the joint has its ends countersunk, as shown in Fig. 2^y. The inner ferrule, *a*, having been attached by its rivet-pin *c*, the outer ferrule, *b*, is passed over the lash, with the large end 70 of the ferrule foremost. This clears the large portion of said ferrule *a*, and, finally, is applied to the handle end and secured by its rivet-pin *c*, or otherwise. The contracted outer end of the outer ferrule now embraces 75 the neck of the inner ferrule, as aforesaid, and coacts with the outer bead in the first form and with the shoulder at the junction of the neck and larger part of the inner ferrule in the second form, so as to preclude the separation 80 of the handle and lash endwise, while they are free to turn independently on the longitudinal axis of the whip. Thus attached the lash adjusts itself automatically, so as to always be in position for use, as aforesaid, 85 and the tendency of the lash in handled whips to break at or near where it is attached to the handle is also thus obviated.

I claim as my invention and desire to patent under this specification—

1. The combination, with a whip handle and lash, of a ferrule, *a*, secured on the large end of the lash, and having a round neck and a relatively large portion beyond the same, and a ferrule, *b*, having a contracted outer end to 95 embrace said neck, and a larger end fitted to the small end of the handle, the same forming a swiveling butt-joint, substantially as and for the purpose hereinbefore described.

2. In a whip having a swiveling butt-joint 100 between its handle and its lash, an inner ferrule, *a*, having a round neck, and a pair of circumferential beads forming a relatively large portion beyond said neck, in combina-

tion with an outer ferrule, *b*, having a contracted outer end to coact with the outermost of said beads, and a rivet-pin, *c*, passing through said inner ferrule, and having projecting beads at both ends between said beads, substantially as and for the purpose hereinbefore described.

In witness whereof I affix my signature in presence of two witnesses.

JOSEPH HOLDING.
